UNITED STATES PATENT OFFICE.

BUTLER EDGAR, OF SUNBURY, PENNSYLVANIA.

DESIGN FOR A RADIATOR.

SPECIFICATION forming part of Design No. 31,046, dated June 20, 1899.

Application filed May 12, 1899. Serial No. 716,585. Term of patent 14 years.

To all whom it may concern:

Be it known that I, BUTLER EDGAR, a citizen of the United States, residing at Sunbury, in the county of Northumberland and State of Pennsylvania, have invented a new and original Design for Radiators, of which the following is a specification.

My invention relates to a new and original design for a radiator or heating-drum.

10 In the accompanying drawings, Figure 1 is a perspective view of a radiator embodying my new and original design. Fig. 2 is a side elevation of the radiator. Fig. 3 is a plan view of the radiator.

15 As shown in the drawings, the leading or material feature of my design is the peculiar form of the radiator.

Referring to the drawings, it will be seen that each of the end walls of the radiator consists of a series of substantially vertical sections A, separated one from the other by angular sections B.

The top and bottom walls of the radiator are, as shown in Fig. 3, substantially square

in form and are provided with flue connections C C'.

Each of the sections A of the end walls of the radiator is of rectangular shape, and the angular sections B, intermediate of said rectangular sections, are arranged within the planes of the outer faces of the end walls, forming reentrant angles.

It will be seen that the angular sections B of one end wall are arranged opposite the rectangular sections A of the other end wall, thereby giving to the sides D the peculiar zig-zag form illustrated.

Having thus described my new and original design for a radiator, what I claim, and desire to secure by Letters Patent, is—

The design for a radiator substantially as herein shown and described.

In testimony whereof I affix my signature in presence of two witnesses.

BUTLER EDGAR.
